UNITED STATES PATENT OFFICE.

LILLIAN G. WALKER, OF BOSTON, MASSACHUSETTS, ASSIGNOR TO THE WALKER CORSET COMPANY, OF MAINE.

CORSET.

SPECIFICATION forming part of Letters Patent No. 681,663, dated August 27, 1901.

Application filed May 11, 1900. Serial No. 16,383. (No model.)

To all whom it may concern:

Be it known that I, LILLIAN G. WALKER, a citizen of the United States, residing at Boston, in the county of Suffolk and State of 5 Massachusetts, have invented a certain new and useful Corset, of which the following is a specification, reference being had therein to the accompanying drawings.

My invention relates to corsets, and has for 10 its object to provide a corset of such construction that when secured in position upon the body of the wearer will support the abdomen and muscles of the bust without compression upon either and will permit freedom 15 of movement to all the muscles of the body, especially those of the bust, sides, abdomen, and chest in any reasonable labor or recreation requiring activity of movement or exercise of the voice in singing or speaking.

20 The particular features of construction by which I secure the results above set forth are hereinafter pointed out in the claims. The most important of these features is the shape given to the front edges of the corset by curving or beveling these lower portions away 25 from the line of their upper portion, so that when the two front edges are clasped together a recess or hollow is formed of such shape as to receive and support the abdomen without 30 compression and without forcing it out of its natural position.

35 A further feature of my construction, and this is of especial importance in connection with the feature above described, consists in so shaping the component parts of which the corset is made up that the seams by which they are united are convex, the seams from the front to the seams immediately above the hips presenting their convexity toward the 40 front edges and those from the back toward the seams immediately above the hips presenting their convexity toward the back. By reason of the features of construction I am enabled to maintain the shape of the corset 45 when in position upon the body of the wearer, particularly the lower portion of the front, and at the same time cut away the sides of the corset, so as to leave the hips entirely free from pressure.

50 A further feature of practical importance in connection with the features above set

forth consists in making the upper part of the corset terminate at the bust-line.

Referring to the drawings, Figure 1 is a side view of the component parts of one-half of 55 my corset, the parts being shown before they are secured together. Fig. 2 is a side view of one-half of my corset laid flat. Fig. 3 is a front view of my corset with its front edges clasped as in use. Fig. 4 is an edge view of 60 the front edge of my corset. Fig. 5 is a front view of the same, showing the curved lower portion; and Fig. 6 is a front view showing the front edge portions of my corset ready to 65 be clasped together.

In the drawings, A indicates one half of my corset. This half-corset is made up of the parts a, b, c, d, e, f, g, h, and i, united by seams, as shown. These parts are of such shape that with the exception of that joining 70 the parts d and e, which is the seam immediately above the hip, the lines of junction between adjoining parts is convex in a greater or less degree, either toward the front or toward the back, as clearly indicated in Fig. 2, 75 the lines of junction between the parts a, b, b, c, and c d being convex toward the front and the lines of junction between the parts e, f, g, g, h, and h i being convex toward the back. The front steel n has its upper portion n' substantially straight, whether viewed in front view, as in Figs. 2, 5, and 6, or in edge view, as in Fig. 4, while its lower portion n² is both concaved inward, as shown in Fig. 4, to fit over the curve of the abdomen, and 80 is also curved or beveled away from the line of its upper portion, as shown in Figs. 2, 5, and 6.

B indicates the other half of my corset, and is made up of parts similar to those of which 90 A is made up, and it will not be necessary to describe these parts in detail. The parts a, b, c, d, e, f, g, g, h, and h i are seamed together from the upper to the lower line of the corset. The parts b, c and d, e are united along a portion 95 of their edges only, the parts b, c being seamed together between the points x, x (see Fig. 1) having the slit m, the upper and lower portions of the edges of these parts being adjustably secured together by the lacing s and s², and the parts d, c being seamed together between the points y, y having the 100

slit *l*, the lower portions of the edges of these parts being adjustably secured together by the lacing *s*'.

n denotes the steels which form the front edges of the corset.

o denotes the bust edge of the corset, *p* denotes the back edge, and *q* the waist edge.

r denotes the parts of the clasp carried by the front steels *n*, and *t* denotes the eyelets arranged along the back edges of the corset to receive the lacing by which the parts *A* and *B* are secured together at the back. The upper ends of the parts *a*, *b*, and *c* extend only to the bust-line for the purpose of elevating and lifting up the bust, thereby giving an appearance of added length to the waist-line in front, the increased length being from half an inch to one inch. The parts *b* *c* may be adjusted by the lacing *s*. The

lower ends of the parts *d*, *e*, and *f* extend only to the waist-line or slightly below it above the hips, making what may be properly termed "hipless" corsets, thereby permitting perfect ease and freedom of movement of the hips

25 and at the same time giving the wearer the appearance of a small waist. The parts *d*, *e*, and *f* may be adjusted by the lacings *s*'. The lower edges of the parts *a*, *b*, and *c* form a long slant from the waist-line just in front of

30 the hip, down over the abdomen to the lowermost point of the front steel *n*, following the natural lines of the body and supporting the abdomen. By reason of the convexity of these parts above described this support is

35 effected without pressure on the abdomen, so that in bending or stooping the flesh instead of being pressed downward is held upward and is allowed to fill this convexity. In this feature of construction my corset differs es-

40 sentially from the ordinary corset, in which the front edge of the front steel is a straight line, the lower portion of the steel being concave, with the result that when the wearer bends or stoops the flesh is pressed downward, making the wearer uncomfortable and un-

45 gainly in appearance.

The ordinary corset, as is well known, presses upon and greatly constricts many important muscles of the body in the region of the stomach, chest, hips, ribs, and back, and is the reverse of easy and comfortable. There is no doubt that many ills and complaints of the body may be traced to the wearing of corsets not made upon hygienic principles, and

55 that the development and growth of the muscles of the body, especially those of the bust, are retarded by the compression caused by its use. The disadvantages of the ordinary corset are avoided by the use of my corset, con-

60 structed as above described, with the convex front steel, and made up of the component parts above described, with the convex lines or seams joining them, and as the convexity of these lines or seams ceases at the sides and

65 from the side seams toward the back are convex in reverse direction, then results such a

perfect adaptation of the corset to the form of the back that the ridge over the shoulder-blades usually made by the general run of corsets is entirely absent, giving the back a 70 beautiful smooth appearance and adding strength and support to the spine.

I believe that a corset constructed as above set forth meets the demand for a hygienic healthful corset adapted to every condition, 75 occupation, or recreation in life, that it can not only be worn without injury to the health by any girl or woman, but that a slim bustless girl or woman may develop a full and natural bust by wearing it, since, unlike other 80 corsets, my corset does not compress the bust and thus interfere with the natural development. A corset made upon the lines described above neither depresses the stomach nor causes inertia of the muscles over the 85 heart, liver, or spine, but adapts itself to the form instead of the form to it. Its use prevents and, if existent, relieves and cures flatulence, dyspepsia, and indigestion, and I believe that the chronic complaints such as 90 flat busts, weakened uterus, and childlessness, if not hopelessly chronic, can be cured by its use and that a perfection, healthfulness, and roundness of form such as a girl in 95 youth should have can be secured by wearing such a corset as I have described.

By the term "bevel" as applied to the form given to the lower portion of the front steel it is not to be understood that I contemplate or intend that the front line of this portion 100 shall form a sharp angle with the upper portion of the steel. On the contrary, while the general direction of this lower portion is at an angle to the line of the upper portion it is united to the upper portion on gently-curving 105 lines substantially as shown, the angle of the general direction of this lower portion being varied, as may be found desirable.

Having thus described my invention, what I claim, and desire to secure by Letters Patent, is—

1. A corset having the lower portion of its front concaved to fit over the abdomen, and having the front edges of said lower portion beveled away, whereby when the front edges 115 are united the concave of the front is maintained without pressure on the abdomen; substantially as described.

2. A corset, cut away above the hips, and having the lower portion of its front concaved to fit over the abdomen, and having the front edges of said lower portion beveled away, whereby when the front edges are united, the concave of the front is maintained without pressure on the abdomen; substantially as described. 120

3. A corset having its upper edge terminating at the bust-line, cut away over the hips, and having the lower portion of its front concaved to fit over the abdomen, and having the front edges of said lower portion beveled away, whereby when the front edges are 125 130

united the concave of the front is maintained without pressure on the abdomen; substantially as described.

4. A corset comprising a series of parts or 5 gores, united by seams, the seams between the front of the corset and the seam directly above the hips, being convex toward the front, and the seams between the back, and the seam directly above the hips, being convex toward 10 the back, the seams directly above the hips being substantially straight, the lower portion of its front concaved to fit over the ab-

domen, and having the front edges of said lower portion beveled away, whereby when the front edges are united the concave of the front 15 is maintained without pressure on the abdomen; substantially as described.

In witness whereof I have hereunto affixed my signature, this 25th day of April, A. D. 1900, in the presence of two witnesses.

LILLIAN G. WALKER.
